M. MOORE

MOLD FOR TILES OR BLOCKS OF CONCRETE

Filed April 18, 1922

Inventor.

Merrill Moore

by Jas. L. Shidmire

his Attorney.

UNITED STATES PATENT OFFICE.

MERRILL MOORE, OF CRESTON, IOWA.

MOLD FOR TILES OR BLOCKS OF CONCRETE.

Application filed April 18, 1922. Serial No. 554,744.

To all whom it may concern:

Be it known that I, MERRILL MOORE, a citizen of the United States, residing at Creston, in the county of Union and State of Iowa, 5 have invented certain new and useful Improvements in Molds for Tiles or Blocks of Concrete, of which the following is a specification.

This invention relates to a novel construction of mold for use in the manufacture of concrete and other composite tile and blocks for building and other purposes, said mold being used with or without a number of different shaped cores adapted to be secured 10 within the mold.

The prime object of the invention is to provide a simple, durable, economical and efficient device especially devised for the purpose of enabling the desired blocks and 20 tiles to be readily and quickly made by unskilled labor.

Another object of this invention is to so construct my improved mold that it will be automatically locked together by the weight 25 of the concrete within the mold, when the said mold is properly filled with the concrete or other composite material.

Another object of the invention is to provide a mold which is always assembled, and 30 so constructed and arranged that the block or tile can readily be removed from the mold without dismantling it, which is necessary in many of the molds now in use.

A further object of this invention is to 35 provide an individual self locking and racking mold, so constructed that the molds may be racked one on top of another until the desired height is reached, thus making it possible to place a large number of molds in 40 a small room, without the use of racks, where the blocks or tile can be cured with artificial heat, thereby saving in both floor space and fuel.

The foregoing and such other objects as 45 may appear from the ensuing description are accomplished by the novel features of construction, arrangement, location and combination of parts hereinafter more fully described, illustrated in the accompanying 50 drawings, and particularly pointed out in the claims appended hereto, it being understood that slight changes in the precise form, proportions, and minor details of con-

struction may be resorted to without departing from the spirit or sacrificing any of the 55 advantages of the invention.

In the accompanying drawings forming a part of this specification, it will be seen that:—

Figure 1 is a central longitudinal section 60 of a mold embodying my invention taken in the plane of the dotted lines 1—1, Fig. 2, showing the mold filled with concrete or other composite material, with a core secured therein.

Figure 2 is a plan view of the same.

Figure 3 is a side elevation showing two empty molds in their racked or stacked position, one resting on the top of another, 70 and

Figure 4 is a transverse section taken in the plane of the dotted lines 4—4, Fig. 2.

Similar numerals of reference are employed to designate like parts throughout the several views of the drawings.

In the embodiment of my invention as illustrated and which shows a preferred construction, the numeral 1 indicates the sides of the mold, 2 the bottom thereof, and 3 the end members, which extend laterally 80 beyond each side of the mold, and stamped inwardly from the end members at each side near the upper end thereof and at a right angle thereto is an integral ear 4, which is adapted to overlap and engage each side portion thereby holding the sides in 85 their normal position and serving to prevent any outward distortion when the molds are fully filled with the composite molding material, said sides, bottom and end members being formed from any suitable sheet metal, which is preferably galvanized to prevent rust from forming upon its surface.

Each end member 3 is bent inwardly the 90 entire width of the mold at the bottom portion thereof, to form an open folded portion 95 beneath the bottom, said folded portion terminating in a downwardly and outwardly inclined member 6 at each end of the mold, said members 6 forming the seating or supporting portions of the mold at all times, and passing through the bottom 2 and the folded portions of each end member is a plurality of bolts 7, provided with threaded ends to each of which is fitted a securing nut 8, said nuts and bolts not being drawn 100

105

up tightly through said folded portions, since the folded portions are left sufficiently open to permit the weight of the mold and molded material within the mold when 5 filled, to cause the folded portions to automatically close together by the entire weight resting on the members 6, thereby causing the end members to remain in the closed position, such as shown in Fig. 1 with the 10 ears 4 overlapping each side of the mold, thus securing the mold in its proper assembled position when filled.

It will be perceived that when the several 15 parts of the mold are united in the manner hereinbefore described it forms a single assembled structure, and that when it is desired to discharge a formed tile or block from the mold, it is simply necessary to grasp the members 6 and then by inverting 20 the mold the ends will automatically open outwardly and allow the easy and ready removal of the tile or block therefrom.

The top portion of each end member is 25 provided with a downwardly and outwardly extended flange 9, so that when it is desired to rack or stack the molds to any desirable height within a room it is simply necessary to seat the lowermost members 6 on the top of the flanges 9 in the manner shown in Fig. 30 3 of the drawings.

It is desired to use cores of different shapes 35 in connection with the mold, and I provide preferably a wooden core 10, having a plate or band of spring steel 11, rigidly secured to the top of each core in any suitable manner, preferably by set screws 12, said plate or band being provided at each end with an overhanging downwardly and outwardly inclined yielding portion 13 adapted to rest between the outwardly projecting fins 14 40 formed on the flanges 9 of the end members, and serving to rigidly hold the end members against the sides during the operation of filling the mold and at the same time secures 45 the core in its proper position within the mold, as clearly shown in Figs. 1 and 2.

In filling the mold the core 10 is placed 50 within the mold, the spring steel band 11, which is fastened to the top of said core retains the core in place and hooks over the ends 3 of the mold, thus serving to hold the ends in contact with the sides while the concrete is being placed therein. After the 55 molds are filled with the concrete the core is removed and the molds are stacked one upon another, the bottom portion of each mold thus retaining the top of the mold below in its closed position, as will be readily understood.

60 It will be readily understood that after the molds shall have been properly filled with the desired molding material the core is removed by grasping the yielding portions 13, at each end thereof, and lifting it from the 65 mold, the molds then being stacked one upon

another, with the bottom members 6 of each mold resting on the top of the flange 9 of the mold below thus holding the end members securely in closed position.

Having thus described my invention what 70 I claim and desire to secure by Letters Patent is:—

1. A mold of the character described comprising sides and a bottom member, and end members each formed with an open folded portion beneath the bottom, said folded portions terminating in an inclined downwardly and outwardly extended inclined portion forming a seat for said mold, and means for 75 yieldingly securing the end members to the bottom.

2. A mold of the character described comprising a member forming the bottom and sides, and end members formed with a yielding folded portion beneath the bottom and a downwardly and outwardly inclined flange formed at the top of each end member, and means for yieldingly securing the end members to the bottom.

3. A mold of the character described comprising a member forming the sides and bottom thereof, and end members formed with an integral yielding folded portion beneath said bottom, said folded portion terminating in a downwardly and outwardly extended inclined portion serving as a seat for the mold, a plurality of integral ears formed on each end member overlapping each side, and means for securing the folded portion of said end members to the bottom.

4. A mold of the character described comprising a member forming the bottom and sides thereof, and end members, each end member being formed with a yielding folded portion beneath the bottom terminating in a support for the mold and a downwardly and outwardly extended flange formed at its top, a plurality of stamped out ears formed on each end member adapted to overlap and contact with each side, and bolts and nuts for yieldingly securing the end members to said bottom.

5. A mold of the character described comprising a member forming the sides and bottom thereof, end members, each end member being bent upon itself at its lower portion beneath the bottom to form a yielding folded portion terminating in a seat for the mold, a downwardly and outwardly extended flange formed at the top of each end member, inwardly extended ears formed near the top of each end member adapted to overlap each side, and means for yieldingly securing the end members to the bottom of the mold.

6. A mold of the character described comprising a member forming the bottom and sides, end members yieldingly secured to the bottom and adapted to be closed against the sides by the weight of the molding material within the mold, and downwardly and out-

wardly inclined means formed on the top and bottom of each end member adapted for stacking the molds one upon another.

7. A mold of the character described comprising a member forming the sides and bottom thereof, end members yieldingly secured to the bottom, means for stacking the

molds formed at the bottom and top of each end member respectively, and a core centrally located within the mold adapted to ¹⁰ lock the end members securely together in contact with the sides of the mold.

MERRILL MOORE.
